UNITED STATES PATENT OFFICE

HENRY E. BUTLER, OF SCOTIA, NEW YORK, ASSIGNEE TO GENERAL ELECTRIC COMPANY,
A CORPORATION OF NEW YORK

CUTOUT FOR SERIES LAMPS

Application filed October 10, 1929. Serial No. 398,765.

In connection with strings of low voltage series lamps, such as are used for lighting Christmas trees and other decorative purposes, the difficulty is met with that in case one lamp burns out all the lamps in the string are extinguished and it then becomes necessary to test the lamps in the string successively until the burned-out lamp is found and then replace it before the string can be put into service again. This is annoying, especially if the lamps are located so that they are not readily accessible, but in spite of such difficulty series strings for the purpose specified are most commonly used because they can be provided at substantially lower cost than strings of parallel connected lamps. Film cutouts for series lighting circuits are well known and are in common use in connection with series street lighting circuits, and this, of course, is a remedy for the difficulty set forth above. However, none of the arrangements in use at the present time are suitable for low voltage series lamps because, among other things, of their high cost.

The object of my present invention is to provide an improved construction and arrangement of film cutout which is so simple in structure, low in cost, and easy to use, that it becomes practical for use in connection with strings of lights such as those used for Christmas tree lighting, and for a consideration of what I believe to be novel and my invention, attention is directed to the following specification and the claims appended thereto.

In the drawings, Fig. 1 is a perspective view of a light of the type used for Christmas tree lighting; provided with a film cutout structure embodying my invention; Fig. 2 is an exploded view of certain of the parts which go to make up the film cutout device, and Fig. 3 is a longitudinal sectional view partly broken away of the complete device.

Referring to the drawings, 1 indicates an electric lamp such as a Christmas tree lamp, 2 indicates the lamp socket and receptacle, and 3 and 4 indicate the two lead wires. It will be understood that a number of lamps similar to lamp 1 are connected in series by the lead wires to form a string. The lead

wires are insulated wires, and in the drawing 5 indicates the conductors of the wires.

According to the embodiment of my invention illustrated in the drawings, I provide a block 6 of insulating material having a longitudinally extending groove 7 therein of a width adapted to receive the wires 3 and 4. Preferably also the block is provided with a transversely extending groove 8 which communicates with groove 7 and through which the wires 3 and 4 project so that the block 6 may extend transversely of the lamp 1, the lamp 1 hanging down below the block. Also groove 7 may be provided at its innermost end with a depression or recess 9 adapted to partially receive the wire so as to hold it in fixed position in the groove. The groove 8, in substance divides the groove 7 into two grooves, one for each lead wire, and viewed from this aspect it may be considered that the block is provided with two grooves, one for each wire. In the upper surface of the block is a recess 10 at the two ends of which are located connectors 11 and 12, adapted to make electrical contact with the conductors 5 of the lead wires 3 and 4. These connectors may be with advantage in the form of screws having pointed ends as indicated at 13 in Fig. 3, whereby the screws may be brought into electrical contact with the conductors by forcing the pointed ends through the insulation as is shown at the left-hand side of the Fig. 3. Joining the two connectors is a conducting member 14 which may be in the form of a suitable resistance, and which, if desired, may be wound on a carrying member 15. At its two ends the conducting member 14 is connected to washers 16 located beneath the heads of screws 11 and 12. Screws 11 and 12, washers 16 and conducting member 14 form a conductor connecting the two wires which conductor is in shunt to the lamp filament and in this conductor I provide a dielectric film which may be in the form of an insulating coating on one of the parts of a character such that at normal voltage it remains intact but in case it is subjected to a voltage a certain amount higher than normal it breaks down or punctures, this being the well understood manner in which a film

100

cut-out functions. As a dielectric film I may use, for example, a thin coating of copper phosphate, copper oxide, aluminum oxide or the like, and such coating may be applied to one of the screws 11 or 12, to one of the washers 16, or to any other part forming a portion of the shunt conductor, or the coating may be applied to two or more of such parts. The essential thing is that the dielectric film be provided in the shunt conductor. The conducting member 14 may have a resistance equal substantially to that of the lamp filament so that when inserted into the series circuit, the brightness at which the remaining lamps burn will not be affected, or it may have a higher resistance whereby when inserted into the circuit it will dim somewhat all the lamps, thus serving as an indication that a lamp has burned out. Or, if desired, conducting member 14 may have relatively small resistances, serving then only as a connector.

In the use of the invention, a film cutout is connected in parallel with each lamp of the string, as shown in Figs. 1 and 3. This is easily done with the use only of a screw driver, it being necessary merely to place the wires 3 and 4 in the grooves and turn down the screws. Recess 9 serves to hold the wires from sliding sidewise when the pointed ends of the screws are being forced through the insulation on the wires. When a lamp burns out, the dielectric film of its film cutout breaks down or punctures due to the higher voltage to which it is subjected and forms a short circuit around the burned out filament. The rest of the string of lamps will continue to burn. At any time a new lamp may be substituted for the burned out lamp, and a new film cutout substituted for the punctured one.

By my invention I provide a film cutout which is very simple in structure, easy to use and capable of being manufactured at low cost. In addition, it has the advantage that it may be used in connection with any string of lamps, its use in no way modifying or changing existing structures. Also, it is so simple that any one can easily apply it to a string of lamps.

In accordance with the provision of the patent statute, I have described the principle of operation of my invention, together with the apparatus which I now consider to represent the best embodiment thereof; but I desire to have it understood that the apparatus shown is only illustrative and that the invention may be carried out by other means.

What I claim as new and desire to secure by Letters Patent of the United States is:

1. A film cutout for series lamps comprising a block having groove means adapted to receive a pair of lead wires, spaced contacts carried by the block and insulated from each other for engagement with the conductors of

the lead wires, and means including a dielectric film connecting said contacts.

2. A film cutout for series lamps comprising a block having groove means adapted to receive a pair of lead wires, spaced contacts carried by the block and insulated from each other for engagement with the conductors of the lead wires, and means including a dielectric film and a resistance in series therewith connecting said contacts. 75

3. A film cutout for series lamps comprising a block having groove means adapted to receive a pair of lead wires, spaced contacts having pointed ends carried by the block, said pointed ends being adapted to pierce the insulation on a lead wire and make engagement with the conductor of the wire, and means including a dielectric film connecting said contacts. 80

4. A film cutout for series lamps comprising an insulating block having a groove portion for each of two lead wires, contact screws having ends which project into said groove portions, and means including a dielectric film connecting said contacts. 85

5. A film cutout for series lamps comprising an insulating block having a groove portion for each of two lead wires, contact screws having ends which project into said groove portions, and means including a dielectric film and a resistance in series therewith connecting said contacts. 90 95

6. A film cutout for series lamps comprising an insulating block having a longitudinally extending groove and a transverse groove communicating therewith, said grooves being adapted to receive lead wires, spaced screws carried by the block and having ends which project into said grooves, and means including a dielectric film connecting 100 105 said screws.

7. A film cutout for series lamps comprising a block, contacts carried by the block and insulated therefrom, said contacts being adapted for connection directly to the lead wires of an electric lamp, and means connecting said contacts, said means including a part coated with a dielectric film. 110

8. A film cutout for series lamps comprising a block, contacts carried by the block and insulated therefrom, said contacts being adapted for connection directly to the lead wires of an electric lamp, and means including a dielectric film and a resistance in series therewith connecting said contacts. 115 120

In witness whereof, I have hereunto set my hand this 9th day of October, 1929.

HENRY E. BUTLER.
